DESIGN FOR A DRESS

Mary Mullen, Philadelphia, Pa., assignor to
Rosenau Bros. Inc., Philadelphia, Pa., a corporation of Pennsylvania

Application March 17, 1937, Serial No. 68,217

Term of patent 3½ years

To all whom it may concern:

Be it known that I, Mary Mullen, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof:

Figure 1 represents a front elevational view of the dress embodying the design.

Figure 2 represents a rear elevational view of the dress embodying the design.

The characteristic feature of the design is the arrangement of the front central pleat, which ex-

tends throughout the entire length of the dress and is provided near the upper portion thereof with a series of closure members, and the grouped series of closely arranged pleats paralleling said front central pleat on each side thereof, said series of closely arranged pleats each extending from the hem line upwardly and being transformed into and terminating in a Shirred pocket-like arrangement in the vicinity of the bodice region and below the collar.

I claim:

The ornamental design for a dress as shown and described.

MARY MULLEN.
